CLAIM

The ornamental design for a snowshoe instep pad, as shown and described.

DESCRIPTION

FIG. 1 is a top perspective view of a snowshoe instep pad embodying my design;

FIG. 2 is a bottom perspective view;

FIG. 3 is a side elevational view;

FIG. 4 is a cross sectional view taken on line 4—4 of FIG. 1;

FIG. 5 is an end elevational view as seen from the left of FIG. 1; and,

FIG. 6 is a top perspective view of a second embodiment of the snowshoe instep pad.
